BEATER FOR PAPER STOCK

Charles R. Seaborne, Appleton, Wis.

Application April 3, 1936, Serial No. 72,509

10 Claims. (Cl. 92—25)

My invention relates to beaters for paper stock and is concerned primarily with the improvement of beaters of the general type disclosed in my Patent No. 1,691,308, which was issued on November 13, 1928.

The principal objects of the present invention are to provide a beater of this general type which shall be capable of sustained operation without clogging of the beater knives over long periods of time; to provide a beater of this type wherein the circulation of pulp shall be effected with a greater positiveness and at a more rapid rate than has been heretofore accomplished; to improve generally beaters of this type; and to provide a simple means readily attachable to existing beaters for preventing clogging thereof during use. Other objects and uses of the invention will be made apparent by reference to the following specification and the drawings, wherein—

20 Fig. 1 is a sectional view, partially in elevation, of a beater embodying the features of my invention. The view is taken on the general line 1—1 of Fig. 2;

25 Fig. 2 is a bottom plan view of the beater illustrated in Fig. 1;

Fig. 3 is an inverted, detail plan view showing the bottom of the bowl and the beater knives positioned thereon;

30 Fig. 4 is a fragmentary view showing the motor operated mechanism for raising and lowering the beater bowl;

Fig. 5 is a perspective view showing one of the scraper knives used in accomplishing the objects of my invention, and

35 Figs. 6 and 7 are fragmentary views illustrating the manner in which the scraper knives shown in detail in Fig. 5 are mounted upon the beater structure.

Referring to the drawings, my improved beater includes a generally cylindrically shaped outer tank or closure 1 which is supported upon a suitable frame 2, which may comprise welded structural sections, as is illustrated in Figs. 1 and 2. The bottom of the outer closure 1 is permanently closed by means such as the metallic plate 3, and the top is likewise closed by a similar plate 4 having a suitable opening 5 through which pulp stock may be introduced into the beater. The beater structure also includes a pressure operated dump valve 6 for withdrawing the pulp at the conclusion of the beating operation and a water inlet pipe 7.

An annularly shaped, cast metallic bowl 8 which is open at its top and bottom is positioned within the outer tank or closure 1 and is provided

with a plurality of downwardly projecting beater knives 9 at the bottom surface thereof.

The bottom of the bowl is normally closed by a rotatable disk or plate 11 having a plurality of beater knives 12 for cooperating with the beater knives 9 of the bowl operatively supported upon the upper surface thereof. The plate 11 is supported for rotatable movement beneath the bowl 8 by means of a vertically extending shaft 13 and a thrust bearing 14, a suitable hub 15 cast integrally with the plate 11 being keyed to the shaft 13. The plate 11 is provided with at least one impeller blade 16 cast integrally with the upper surface thereof for aiding in effecting the circulation of the pulp through the beater knives. If desired, peripherally arranged vanes as are indicated at 16' may be used for further increasing the speed and effectiveness of the pulp circulation.

During operation of the beater, the pulp or other stock, the normal level of which is indicated by the dot and dash line 17, is circulated within the bowl 8 and the outer closure 1 in the manner indicated by the arrows. In order to aid in securing vertical movement of the pulp within the bowl and hence more positive circulation of the pulp between the cooperating sets of beater knives, I have provided a feeder screw 18 which is supported upon and keyed to the shaft 13. This feeder screw is preferably of hollow, cast metallic construction as illustrated in the drawings, but other arrangements are, of course, satisfactory.

For rotating the plate 11 which closes the bottom of the bowl 8, and the feeder screw 18, I prefer to utilize an electric motor indicated at 19, in conjunction with a suitable speed changing mechanism indicated at 20, this mechanism being mechanically coupled with the upper end of the shaft by any suitable means. The motor and the speed changing mechanism are supported upon a suitable frame or superstructure 38 at the top of the beater.

For most satisfactory operation of a beater of this type, it is desirable that the cooperating sets of beater knives shall be vertically adjustable with respect to each other. In the device illustrated in the drawings this adjustment is made possible by the provision of a vertically adjustable support means for the bowl 8. This support means comprises three symmetrically positioned mechanisms 21, each of which includes a thrust rod 24 adapted to be affixed to the bottom of the bowl 8, and an adjustable lift screw 22 for raising and lowering the thrust rod. The lift screws 22

are each actuated by a sprocket wheel 23, and in order that vertical adjustment of the bowl can be most conveniently carried out, the sprocket wheels 23 are interconnected by a chain 5 25 which also engages the sprocket drive wheel 26 of the motor operated bowl raising and lowering mechanism 27, illustrated particularly in Figs. 1 and 4. The motor drive of this mechanism 27 preferably includes a speed reducing 10 gearing indicated at 28, this arrangement permitting very close vertical adjustment of the co-operating sets of beater knives 9 and 12. The bowl supporting mechanism 21 includes yieldable means intermediate the thrust rods 24 and the 15 lift screws 22 which permits momentary upward movement of the bowl to prevent damage to the beater knives in the event that some foreign object should get into the beater.

In the operation of beaters of the type disclosed 20 in my earlier Patent No. 1,691,308, some difficulty is at times experienced with clogging of the beater knives during the beating operation, particularly when utilizing certain types of pulp stock. This clogging occurs as the stock flows 25 outwardly through the knives, some of it having a tendency to staple or jackknife in the space between the stationary and rotating blades. While this clogging in no sense renders the beater inoperative, it substantially impairs its efficiency, 30 particularly when a feeder screw is utilized, the clogging then preventing the full realization of the increased speed of circulation possible with such a structure.

I have found that this clogging can be completely obviated by the provision of one or more 35 of the scraper knives 30, illustrated particularly in Figs. 1, 2, 5, and 7. Preferably a plurality of these knives 30 are supported at spaced intervals upon the inner surface of the bowl 8, the leading 40 edge of the knife portion 31 thereof pointing in a direction opposite to the normal direction of the rotation of the plate 11. The scraper knives 30 are positioned immediately in front of the cooperating beater knives 9 and 12, the resulting 45 scraping action, particularly when aided by the shearing effect of the vane 16, produces a substantially continuous cleaning of the space immediately in front of the cooperating beater knives 9 and 12.

50 The scraper knives 30 are preferably adjustable to at least a slight degree in order that the most efficient scraping action may be effected. Adjustment of the specific form of scraper knives illustrated in the drawings is made possible 55 through the provision of slotted openings 32 for the shanks of the cap screws 33 utilized in affixing the scraper knives to the bowl proper.

From the foregoing it will be seen that I have 60 provided a new and improved form of beater which possesses numerous advantages over the constructions heretofore known to the art. My improved beater includes means for continuously 65 scraping accumulations of pulp from in front of the cooperating beater knives and thus makes possible a substantial increase in the speed of 70 operation of the beater. Further, I have shown how this continuous scraping action may be utilized in conjunction with high speed feeder screws or the like for accomplishing very much more rapid beating of the pulp than has been heretofore possible. I have also disclosed a simple type of scraper knife which may be conveniently applied to existing beater structures for improving the operation thereof.

75 Various modifications may be made in the par-

ticular structure and arrangements of my invention without departing from the principles which I have disclosed above, and it is my intention, therefore, that the accompanying claims shall be construed as broadly as is possible consistent with the state of the art. 5

I claim the following as my invention:

1. A machine of the character described comprising a bowl open at its top and bottom and having its bottom provided with beater knives, 10 a rotatable plate extending beneath and closing the bottom of said bowl, said plate having beater knives for cooperating with the beater knives of the bowl, and at least one scraper knife supported upon said bowl adjacent said rotary plate for 15 preventing clogging of said knives during use of said machine.

2. A machine of the character described comprising a bowl open at its top and bottom and having its bottom provided with a plurality of 20 beater knives, the cutting edges of which extend in a generally horizontal direction, a rotatable plate extending beneath and closing the bottom of said bowl, said plate having a plurality of beater knives, the cutting edges of which likewise 25 extend in a generally horizontal direction for cooperating with the knives of the bowl, and means for preventing clogging of said knives during the use of said machine comprising at least one generally vertical scraper knife supported 30 upon said bowl adjacent said cooperating beater knives.

3. A machine of the character described comprising a bowl open at its top and bottom and having its bottom provided with beater knives, a 35 rotatable plate extending beneath and closing the bottom of said bowl, said plate having beater knives for cooperating with the beater knives of the bowl, and means for preventing the stock from stapling or jackknifing as it flows through 40 and between said cooperating knives, said means comprising a plurality of scrapers adjustably mounted upon said bowl.

4. A machine of the character described comprising a bowl open at its top and bottom and 45 having its bottom provided with beater knives, a rotatable plate extending beneath and closing the bottom of said bowl, said plate having knives for cooperating with the knives of said bowl, a feeder screw disposed within said bowl for circulating the pulp in a vertical direction therein, 50 means for rotating said feeder means and said plate during the operation of said machine, and means for preventing clogging of said beater knives during the operation of said machine, said last mentioned means comprising at least one 55 stationary scraper knife supported inside said bowl adjacent said cooperating beater knives.

5. A machine of the character described comprising a bowl open at its top and bottom and 60 having its bottom provided with beater knives, a rotatable plate extending beneath and closing the bottom of said bowl, said plate having beater knives for cooperating with the beater knives of said bowl, a feeder screw arranged for rotation 65 within said bowl for circulating the pulp in a vertical direction within said bowl, a receptacle for pulp surrounding said knives communicating with the top of said bowl, means for simultaneously rotating said rotatable plate and said feeder 70 screw, and means for preventing clogging of said beater knives comprising a plurality of spaced stationary scraper knives adjustably supported upon the inner surface of said bowl adjacent said co-operating beater knives. 75

6. A machine of the character described, comprising a bowl open at its top and bottom and having its bottom provided with beater knives, a plate extending beneath and closing the bottom of said bowl, said plate being provided with beater knives for cooperating with the beater knives of said bowl, means for imparting rotation to one set of said knives and the part carrying the same, and means comprising at least one scraper knife supported upon said bowl adjacent the area of entry of the stock between said cooperating beater knives for preventing the clogging thereof during use of said machine.

7. A machine of the character described, comprising a bowl open at its top and bottom and having its bottom provided with a set of beater knives, a plate extending beneath and closing the bottom of said bowl, said plate being provided with a second set of beater knives for cooperating with the beater knives of said bowl, means for imparting rotation to one set of beater knives and the part carrying the same, a feeder screw positioned within said bowl for forcing the stock to circulate in a vertical direction, and at least one scraper knife supported upon said bowl adjacent said cooperating beater knives for preventing the clogging thereof during use of said machine.

8. A machine of the character described, comprising a bowl open at its top and bottom and having its bottom provided with beater knives, a rotatable plate extending beneath and closing the bottom of said bowl, said plate being provided with beater knives for cooperating with the beater knives of said bowl and with at least one impeller blade arranged to move within said bowl, means for rotating said plate, and at least one scraper knife supported upon said bowl adjacent

said cooperating beater knives, said impeller blade and said scraper knife cooperating to aid in preventing clogging of said knives during use of said machine.

9. A machine of the character described, comprising a bowl open at its top and bottom and having its bottom provided with a set of beater knives, a rotatable shaft located centrally within said bowl, a feeder screw supported upon said shaft within said bowl, a plate provided with a set of beater knives for cooperating with the beater knives of said bowl also supported on said shaft, said plate extending beneath and closing the bottom of said bowl, means for rotating said shaft, and at least one scraper knife supported upon said bowl adjacent said cooperating beater knives for preventing the clogging thereof during the use of said machine.

10. A machine of the character described, comprising a tank, a bowl disposed within said tank so as to be spaced some distance from the walls thereof, said bowl being open at its top and bottom and having its bottom provided with beater knives, a rotatable plate extending beneath and closing the bottom of said bowl, said plate being provided with beater knives for cooperating with the knives of said bowl and having upon its upper surface at least one impeller blade, a feeder screw located within said bowl substantially coaxially with the axis of rotation of said plate, means for rotating said plate and said feeder screw, and at least one scraper knife mounted on said bowl adjacent the area of entry of the stock between said cooperating beater knives, said impeller blade and said scraper knife cooperating to aid in preventing the clogging of said beater knives during the use of said machine.

CHARLES R. SEABORNE.
